CLAIM

The ornamental design for a wearable device for heating and cooling, as shown and described.

DESCRIPTION

FIG. 1 is a bottom perspective view of a wearable device for heating and cooling;

FIG. 2 is a front elevation view of the wearable device for heating and cooling of FIG. 1;

FIG. 3 is a rear elevation view of the wearable device for heating and cooling of FIG. 1;

FIG. 4 is a top view of the wearable device for heating and cooling of FIG. 1, the bottom being a mirror image thereof;

FIG. 5 is a broken and enlarged view of FIG. 4;

FIG. 6 is an enlarged right side elevation view of the wearable device for heating and cooling of FIG. 1; the left side elevation being a mirror image thereof;

FIG. 7 is an enlarged cross sectional view of the wearable device for heating and cooling of FIG. 1;

FIG. 8 is a bottom perspective view of an alternate embodiment of the wearable device for heating and cooling of FIG. 1;

FIG. 9 is a front elevation view of the alternate embodiment of the wearable device for heating and cooling of FIG. 8;

FIG. 10 is an enlarged right side elevation view of the alternate embodiment of the wearable device for heating and cooling of FIG. 8; the left side elevation being a mirror image thereof; and,

FIG. 11 is an enlarged cross sectional view of the alternate embodiment of the wearable device for heating and cooling of FIG. 8.

The broken lines illustrate environmental structure and form no part of the claimed design.
